INVENTOR
DANIEL J. MURNANE

BY *Charles S. Evans*
HIS ATTORNEY.

UNITED STATES PATENT OFFICE.

DANIEL J. MURNANE, OF SAN MATEO, CALIFORNIA, ASSIGNOR TO NON-PRESSURE GLAZING COMPANY, OF SAN FRANCISCO, CALIFORNIA, A CORPORATION OF CALIFORNIA.

SASH.

Application filed January 24, 1928. Serial No. 249,030.

My invention relates to window sash, and particularly to metal sash such as are used for holding heavy plate glass used in store front construction.

5 An object of my invention is to provide a sash which will hold the glass firmly but which will not subject it to rigid or unyielding pressure which might cause breakage.

10 Another object of my invention is to provide a sash which is sufficiently small in bulk to be applicable to bank doors or similar uses for which older constructions are ill adapted.

15 Still another object of my invention is to provide a sash which allows the glass to be set without the use of any tools other than a screw driver, and which may be easily assembled in inverted position or in a cramped space.

20 My invention possesses other objects and valuable features, some of which will be set forth in the following description of my invention which is illustrated in the drawings forming part of the specification. It is to be understood that I do not limit myself to 25 the showing made by the said description and drawings, as I may adopt varying forms of my invention within the scope of the claims.

Referring to the drawings:

30 Fig. 1 is a sectional view of the assembled sash, the plane of section being normal to the surface of the glass.

Fig. 2 is an elevation of the assembled sash.

35 Fig. 3 is a cross-sectional view of the stationary sash-bar, and Fig. 4 is a similar view of the movable sash-bar.

Fig. 5 is a view in plan of the clamp bracket, the direction of this view being indicated by the arrow 5 of Fig. 3.

40 Fig. 6 is an elevation of the movable sash-bar, the direction of the view being shown by the arrow 6 of Fig. 4.

In terms of broad inclusion, the sash of my invention comprises a stationary sash-bar 45 which is provided with a lip or flange for fitting against the glass, and is secured to the window frame. Projecting past the glass from the stationary sash-bar at suitable intervals are U or channel-shaped clamp brackets having open slots formed in their ends. The glass rests against the fixed sash-bar, supported on the usual blocks, and is held in place by the movable sash-bar.

The general conformation of the movable

bar is that of the letter L whose foot rests on the clamp bracket. A lip is provided on the riser of the L to seat against the glass, and a second lip or flange extends downwardly from the toe of the L to cover the ends of the brackets and complete the closure to the window frame. Clamp screws pass thru the foot of the L and turn in nuts which enter the channel brackets as the screws are slid into the open slots and clamp the bar in place when the screws are tightened. Means are 60 provided for holding the screws in tension and preventing the nuts from turning, so that the nuts readily enter the channels regardless of the position in which the sash-bar is held. There is no direct localized pressure upon the glass, the resilience of the angle construction distributing the pressure gently 65 and uniformly.

Describing a preferred embodiment of my invention in detailed terms, the stationary 70 sash-bar, comprising a foot 6, a riser 7, and a lip 8 is secured to the frame 9 by the screws 11. The lip is formed in an ogee curve to provide a flat flange against which the glass 12 may rest, and a channel into which condensation from the glass may drain, escaping thru the holes 13. The glass is supported upon spaced blocks in the usual way, these blocks being omitted from the drawing to avoid confusion.

85 Securely held against the stationary sash-bar by the screws 11 are the clamping brackets. The screws pass thru a tab 16 formed from an extension of the central web 17 of the U or channel section into which the 90 brackets are formed. The web 17 has ridges 18 at the sides, increasing in height along the bracket, so that the web itself slopes down and away from the leg 7 of the stationary bar. An open slot 19 is formed in the end of the 95 bracket to admit a clamp screw, and the inner face of the web 17 may conveniently be roughened to form a seat for the clamp-nut. The legs 21 of the channel rest on the foot 6 of the stationary bar, and are cut away to form 100 a gap 22 in the portion adjacent the slot 19.

The movable sash-bar is also of angle or L-shaped section. The top of the leg 25 is bent back and down to form a flange 26 which seats against the glass. Both legs of the 105 angle are preferably provided with beads 27 to improve the strength and appearance of the bar. At intervals corresponding with

the spacing of the clamp brackets the foot 28 of the bar is provided with countersunk holes 29 for preferably oval-headed clamp screws 31. Threaded on the clamp screws and retained by upset ends 32 on the screws are the clamp-nuts 33. These are preferably rectangular in shape and are provided with a tapered end 34 to facilitate their entrance into the space within the channel brackets. Secured to the clamp-nuts, conveniently by the rivets 36, are the leaf springs 37 which bear against the foot of the sash-bar and hold the screws 31 in tension. The outer end of the foot 28 is bent to form a lip or flange 38, covering the ends of the brackets and completing the closure of the sash with the window frame 9. The springs 37 also serve to prevent the rotation of the nut 33 by bearing against this flange. Small gaps 39 are formed at intervals in the flange to provide drainage for the space within the sash.

In setting the glass it is first positioned upon its blocks against the stationary sash-bar, and then the movable sash-bar is slipped into place against it, the screws 31 entering the slots 19, and the clamp-nuts 33 sliding easily into place within the brackets due to their being positioned by the springs. When the movable bars are firmly pressed against the glass the screws are tightened, and the operation is complete. The resilience of the bar structure equalizes the pressure on the glass and prevents breakage. The inclined seat formed for the clamp-nut on the brackets results in any slipping of the clamp increasing the tension on the clamping screw, so that it jams against further movement, and thus provides a maximum of security with a very light simple, and compact structure.

40 I claim:

1. A sash for holding glass comprising a stationary sash-bar, a plurality of brackets having open slots in the ends thereof fixed to said sash-bar, a movable sash-bar, screws in said movable bar positioned to enter said slots, nuts for said screws, and means for preventing the rotation of said nuts.

50 2. A sash for holding glass comprising a stationary sash-bar, a plurality of brackets having open slots in the ends thereof fixed to said sash-bar, a movable sash-bar, screws in said movable bar positioned to enter said slots, nuts for said screws, and resilient means fixed to said nuts for holding said screws in tension.

60 3. A sash for holding glass comprising a stationary sash-bar, a plurality of brackets having open slots in the ends thereof fixed to said sash-bar, a movable sash-bar, screws in said movable bar positioned to enter said slots, nuts for said screws, and resilient means fixed to said nuts for preventing their rotation and for holding said screws in tension.

65 4. A sash for holding glass comprising a stationary sash-bar, a plurality of brackets

having open slots in the ends thereof fixed to said sash-bar, a movable sash-bar, screws in said movable bar positioned to enter said slots, nuts for said screws, and a leaf-spring attached to each of said nuts and bearing 70 against said movable sash-bar.

5. A sash for holding glass comprising a stationary sash-bar, a bracket attached thereto and having an open slotted end extending beyond the glass, an inclined seat formed on 75 said bracket, a movable sash-bar, and clamping means on said movable sash-bar for entering the bracket slots and engaging said seat.

6. A sash for holding glass comprising a stationary sash-bar, a bracket attached thereto and having an open slotted end extending beyond the glass, an inclined seat formed on 80 said bracket, a movable sash-bar, a clamp screw thru said movable sash positioned for entering the bracket-slot, a nut on said screw for engaging said seat, and means for preventing the rotation of said nut.

7. A sash for holding glass comprising a stationary sash-bar, a channel-shaped bracket attached thereto and having an open-slotted 90 end projecting beyond the glass, an inclined seat formed within the channel of said bracket, a movable sash-bar, clamping means on said movable sash-bar for entering the bracket slot and engaging said seat, and resilient means for holding said clamping means in position to facilitate entrance into said slot.

8. A sash for holding glass comprising a stationary sash-bar, a channel-shaped bracket attached thereto and having an open-slotted end projecting beyond the glass, an inclined seat formed within the channel of said bracket, a movable sash-bar, a clamping screw thru 100 said movable sash bar positioned for entering the bracket slot, a nut on said screw, and resilient means for preventing the rotation of said nut and positioning it to facilitate its entrance into said channel to engage said seat.

9. A sash for holding glass comprising an L-shaped stationary sash-bar, a bracket having an open-slotted end attached thereto and extending beyond the glass, an L-shaped movable sash-bar, a clamp screw thru the foot of 110 said movable sash-bar positioned to enter the bracket slot, a nut on said screw, and means for preventing said nut from turning with the screw.

10. A sash for holding glass comprising an L-shaped stationary sash-bar, a bracket having an open-slotted end attached thereto and extending beyond the glass, an L-shaped movable sash-bar, a clamp screw thru the foot of 120 said movable sash-bar positioned to enter the bracket slot, a nut on said screw, and a spring bearing against the foot of said movable sash-bar and positioning said nut.

11. A sash for holding glass comprising a stationary sash-bar, a bracket attached to said sash-bar, an inclined seat formed on said 130

bracket, movable sash-bar, and clamping means arranged on said movable sash-bar engaging said inclined seat and jamming thereon against outward movement of said movable sash-bar.

12. A sash for holding glass comprising a stationary sash-bar, a channel-shaped bracket attached thereto and having an end extending beyond the glass, a movable sash-bar seating on the extending end of said bracket, and clamping means arranged on said movable sash-bar and seating within said channel-shaped bracket.

13. A sash for holding glass comprising a stationary sash-bar, a bracket attached there-

to and having an end extending beyond the glass, a movable sash-bar seating on the extending end of said bracket, and means for clamping said movable sash-bar to the stationary sash-bar.

14. A sash for holding glass comprising a stationary sash-bar, a plurality of slotted brackets fixed thereto, a movable sash-bar, and clamping means carried by said movable sash-bar and operating thru the slots in said brackets adjustably to connect the movable sash-bar with the stationary sash-bar.

In testimony whereof, I have hereunto set my hand.

DANIEL J. MURNANE.
